UNITED STATES PATENT OFFICE.

JOHN K. HARTLINE, OF ALBUQUERQUE, NEW MEXICO.

TESTER.

Application filed November 9, 1925, Serial No. 67,991. Renewed April 4, 1927.

This invention relates to means designed for testing the tube of a locomotive super-heater, and comprehends a construction and arrangement of parts which permit the invention to be easily and quickly associated with or removed from the tube as the occasion may require, and accomplish the desired results in quick order.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

23 Figure 1 is a view in elevation of one of the devices constituting the subject matter of the invention.

Figure 2 is a view taken at a right angle to Figure 1, partly in section.

25 Figure 3 is a sectional view on line 3—3 of Figure 2.

Figure 4 is a sectional view on line 4—4 of Figure 2.

Figure 5 is an enlarged fragmentary view 30 of the upper portion of the device showing how the sliding head is mounted.

Figure 6 is a sectional view taken through Figure 5 and at a right angle thereto.

The device forming the subject matter of the present invention embodies a base plate or block 10 which is provided with a slot or opening 11 to allow the same to be slipped over one of the tubes of the super-heater to be tested. Supported by this base 35 or block 10 are spaced parallel standards or uprights 12, each formed with a fork-like extremity, with the branches 13 thereof passed through openings in the base 10 and secured thereto by nuts 14 threaded on said 40 branches above and below the base. The upper end of each standard is slotted or cut away as at 15 to slidably receive a bearing block 16, the cut away portion 15 being closed by a transverse member or block 17 45 which is held in position by means of suitable fastening elements 18. This transverse member 17 also supports an adjusting screw 19 which is utilized to adjust the bearing block 16 as the occasion may require. As 50 above stated, the base 10 is adapted to be slipped over one of the tubes of the super-

heater, the device including a slidable head 20 which cooperates with the base 10 for clamping the device in position for use. In other words, the base plate 10 is adapted to be slipped over the tube directly beneath the flange that is usually provided adjacent the upper end of the tube, and when the head 20 is moved into effective engagement with the upper end of the tube, the base plate 10 60 engages the flange above mentioned and thereby holds the device on the tube for use. The head 20 is adapted to slide between the parallel uprights or standards 12 and is provided with a fluid passage or bore 21 which 65 communicates with a port 22 arranged at a right angle to said passage, and which port accommodates a fluid supply pipe 23. The underside of this head 20 is recessed to accommodate a gasket 24, so that when the 70 head 20 is moved downwardly to engage the adjacent end of the tube with which the device is associated, a fluid-tight connection 75 will be provided for between the head and tube, as will be readily understood. It might 80 here be stated that in testing the tubes of the super-heater, there are two of such devices employed, which devices are associated with their respective tubes in a manner to allow the fluid from the pipe 23 to pass 85 or circulate through the tubes and through said devices for the purpose intended.

While any suitable means may be employed for controlling the movements of the head 20, I preferably make use of a U-shaped member 25, the parallel portions of which are indicated at 26 and arranged between the uprights or standards 12. The member 25 is provided with spaced openings through which pass headed bolts 27, the 90 openings therefor being indicated at 28, and these bolts have their lower extremities threaded into the head 20, as at 29. Now surrounding each bolt is a coiled spring 30 which provides a yieldable connection between the U-shaped member 25 and the head 20, to hold this head effectively seated against the particular tube with which it is used. For the purpose of raising and lowering the head I employ a lever 31 forked 95 at one end, and the branches of this extremity are indicated at 32. Each branch is connected with the adjacent bearing block 16 above referred to by means of a bolt or the like indicated at 33, which bolt passes 100 through the particular branch of the lever, a disk 34 carried by the U-shaped member 25

and the bearing block 16. This construction and arrangement is clearly shown in Figure 6. The lever pivots on these bolts 33, while the lever, or the branches 32 thereof are riveted or otherwise suitably secured, as at 35, to the adjacent disks 34. There are two of these disks, one for each parallel portion 26 of the U-shaped member, which portion is provided with an opening to accommodate the disk, as shown in Figure 6. Consequently, when the lever 31 is swung in one direction, the disks 34 are rotated to force the U-shaped member 25 downwardly between the standards 12, thereby exerting a pressure upon the springs 30 to move the head 20 into engagement with the adjacent tube and hold it so effectively associated therewith as to prevent leakage of fluid passing through the device.

20 While it is believed that from the foregoing description the nature and advantages of the invention will be readily apparent, I desire to have it understood that I do not limit myself to what is herein shown and described, and that such changes may be resorted to when desired as fall within the scope of what is claimed.

Having thus described the invention, what is claimed as new, is:—

30 1. A device of the character described comprising a base having a slot opening at one side thereof, spaced standards rising from the base, a member supported by the

standards for sliding movement therebetween, a head arranged between said standards and suspended from said member, a yieldable connection between the member and said head, a lever associated with said member for controlling the movements of the latter between said standards, said head 35 having a fluid passage arranged axially thereof, and a fluid supply pipe communicating with said passage.

2. Means for testing tubes of a superheater, comprising devices adapted to be supported on the tubes, each device including a base having a slot to receive one of said tubes, spaced uprights rising from the base, a substantially U-shaped member supported between the uprights for sliding movement, a head suspended from said U-shaped member for movement therewith and adapted to repose on the upper end of the adjacent tube, said head having a fluid passage and a recess in the bottom thereof, a gasket embedded in the walls of said recess to provide a fluid-tight connection between the head and said tube, a fluid supply pipe communicating with said passage, a yieldable connection between the head and U-shaped member, and means for controlling the movements of said member and holding the head effectively seated against the tube.

In testimony whereof I affix my signature.

JOHN K. HARTLINE.
